UNITED STATES PATENT OFFICE

ELMER H. SMITH, OF ENDICOTT, NEW YORK, ASSIGNOR TO ENDICOTT JOHNSON CORPORATION, OF ENDICOTT, NEW YORK, A CORPORATION OF NEW YORK

MACHINE FOR SCRUBBING AND OILING LEATHER

Application filed December 23, 1927. Serial No. 242,235.

This invention is a novel improvement in leather scrubbing and oiling machines, and the principal object thereof is to provide a simple and efficient machine particularly 5 adapted to scrub, by a brushing operation, sheets of sole leather and the like sprayed with hot water and passing through the machine for the purpose of cleaning the leather, and then to fill the scrubbed leather with 10 an oiling compound in order to make the leather flexible, and then to brush the oiling compound into the leather.

Heretofore, oiling compounds have been applied to leather by means of a hose which 15 sprayed the compound over the leather as as leather passed over spraying tables, so-called. These tables were usually fitted with depressions or grooves into which the oiling compound flowed, the compound then 20 flowing back into a storage tank from which it was later re-pumped through the hose and sprayed over other pieces of leather. In this operation obviously the oiling compound became polluted with ingredients 25 extracted from the leather itself, including dirt and grease, so that after three or four hours' use the entire tank full of oiling compound had to be thrown away. This procedure was hence very wasteful.

30 My machine, however, as will be herein-after explained, maintains the oiling compound clean and pure, since the machine applies to the leather only enough compound in each case as is needed for the particular 35 piece of leather being treated.

I will explain the invention with reference to the accompanying drawings which 40 illustrate one practical embodiment thereof to enable others familiar with the art to adopt and use the same, and will summarize in the claims the novel features of construction, and novel combinations of parts, for which protection is desired.

45 In said drawings:

Figure 1 is a side elevation of the machine showing the chain and sprocket drives for rotating the carrier and brush shafts, and showing in dot and dash lines the main 50 drive shaft.

Fig. 2 is a broken top plan view of the complete machine.

Fig. 3 is a longitudinal sectional view through the machine.

Fig. 4 is a plan view of the chain and 55 sprocket drives for the carrier shafts.

Fig. 5 is a detail of the yieldable bearings for the brush shafts.

As shown in the drawings, the machine 60 preferably consists of a rectangular frame, comprising four vertically disposed corner posts or angle irons 1^a, 1^b, 1^c, 1^d, connected together at their lower ends by side bars 1^e and end bars 1^f. The upper ends of posts 1^a, 1^b, and posts 1^c 1^d, are connected together 65 by end bars 1^g.

Intermediate the corner posts 1^a, 1^d, and posts 1^b, 1^c, at each side of the frame are posts 1^h, 1ⁱ. Corner posts 1^a, 1^b, are preferably shorter than corner posts 1^c, 1^d, and shorter than intermediate posts 1^h, 1ⁱ—the 70 four latter posts being substantially the same height. Preferably the entire frame is built up of angle-irons or other structural shapes. Suitable bracing members may be 75 provided, if and where needed.

Extending between the posts 1^a, 1^h, and posts 1^b, 1ⁱ, at the sides of the frame are horizontally disposed beams 1^k, 1^m, disposed at a convenient height below the upper ends 80 of said posts; and between the posts 1^a, 1^d, and the posts 1^h, 1^c, are horizontally disposed beams 1ⁿ, 1^p, preferably disposed at a higher elevation than beams 1^k, 1^m, said beams 1^k, 1^m, 1ⁿ and 1^p, being adapted to 85 support the bearings for the carrier shafts, hereinafter referred to.

Mounted in suitable bearings upon the horizontal beams 1^k, 1^m are four parallel horizontally disposed carrier shafts, 2, 3, 4, 90 and 5. On shafts 2, 3, 4, and 5 respectively, are a series of carrier disks or wheels 2^a, 3^a, 4^a, and 5^a, respectively, all of same diameter and arranged in staggered relation upon the shafts as shown, the wheels of one shaft overlapping the wheels of the adjacent shafts as shown in Fig. 3, and the wheels together forming an endless conveyor for moving the leather sheet L (shown in dotted lines in Fig. 3) through the machine. 95

55

60

65

70

75

80

85

90

95

100

Similarly, three parallel horizontally disposed carrier shafts 6, 7, and 8 are mounted in suitable bearings upon the horizontal beams 1^a, 1^b, said shafts being disposed 5 parallel with the shafts 2, 3, 4, and 5, but in a higher plane than the latter; said shafts 6, 7 and 8 being likewise provided with series of staggered carrier disks or wheels 6^a, 7^a, and 8^a, respectively of same size as wheels 10 2^a, 3^a, 4^a, and 5^a, and shafts 6, 7, and 8, and forming a continuation of the endless conveyor for the leather L passing through the machine.

Intermediate the shafts 5 and 6 is a 15 parallel shaft 9 mounted in suitable bearings fixed to the sides of intermediate posts 1^h, 1^j; the axis of shaft 9 lying in the plane of the axes of shafts 5 and 6. Shaft 9 is likewise provided with a series of carrier 20 disks or wheels 9^a which are staggered in relation to and overlap the wheels 5^a and 6^a of shafts 5 and 6; said wheels 9^a forming a means for passing the leather L from the lower level of shafts 2, 3, 4, and 5, to the 25 higher level of shafts 6, 7, and 8, whereby as the leather L is passed through the machine from the shaft 2 towards the shaft 8, the wheels 9^a of shaft 9 will carry the leather in an inclined plane from the lower 30 level to the upper level of the carrier shafts.

Shafts 2, 3, 4, 5, 9, 6, 7, and 8, extend beyond the frame members 1^m, 1^p, as shown in Figs. 1 and 4 and are provided with the chain sprockets for driving the shafts as 35 hereinafter explained.

On shaft 2 is a sprocket 2^b, and on shaft 3 is a sprocket 3^b around which runs a chain 10, the sprocket 3^b having one less tooth than the sprocket 2^b whereby shaft 3 will 40 rotate slightly faster than shaft 2. On shaft 3 is a second sprocket 3^c, and on shaft 4 is a sprocket 4^b, around which runs a chain 11; sprocket 4^b having one less tooth than the sprocket 3^c, whereby shaft 4 will 45 rotate slightly faster than shaft 3. Similarly, a chain 12 runs around sprockets 5^b and 4^c on shafts 5 and 4 respectively, sprocket 5^b having one less tooth than sprocket 4^c whereby shaft 5 will rotate 50 slightly faster than shaft 4; also, a chain 13 runs around sprockets 9^b and 5^c on shafts 9 and 5 respectively, sprocket 9^b having one less tooth than sprocket 5^c; also a chain 14 runs over sprockets 6^b and 9^c on shafts 55 6 and 9 respectively, sprocket 6^b having one less tooth than sprocket 9^c; also a chain 15 runs over sprockets 7^b and 6^c on shafts 7 and 6 respectively, sprocket 7^b having one less tooth than sprocket 6^c; and a chain 16 60 runs around sprockets 8^b and 7^c on shafts 8 and 7 respectively, sprocket 8^b having one less tooth than sprocket 7^c.

From the above description it will be 65 readily understood that each shaft progressing from shaft 2 to shaft 8 rotates

slightly faster than the preceding shaft, for the purpose hereinafter set forth. Shaft 8 is positively driven by means of a chain 17 which runs over a sprocket 18^a on a power shaft 18 (hereinafter referred to) and over a sprocket 8^c on the end of shaft 8, as shown in Figs. 1 and 2.

Between the posts 1^h, 1^j, respectively, and uprights 1ⁱ, 1^k, respectively, are vertically adjustable horizontally disposed beams 19 and 20, disposed parallel with and above the fixed horizontal beams 1^a, 1^b, said beams 19 and 20 being adjustably connected to the upper ends of the posts 1^h, 1^j, 1ⁱ and 1^k. Beams 19 and 20 are provided with bolts 19^b, 20^b, at their ends adjacent the uprights 1ⁱ, 1^k, which bolts pass through slots 1^r vertically disposed in the sides of uprights 1ⁱ, 1^k. Depending from the end beam 1^k, at the tops of the uprights 1ⁱ, 1^k, above the beams 19 and 20, are adjustable bolts 19^b, 20^b which engage the beams 19 and 20 to support the rear ends of same in desired elevation. Similarly, the beams 19, 20, are provided adjacent the uprights 1^h, 1^j, with bolts 20^c, adapted to pass through slots 1^r in the uprights 1^h, 1^j, the adjacent ends of the beams 19 and 20 being supported by adjustable bolts 19^d, 20^d, engaging brackets 1^s on the sides of the posts 1^h, 1^j. Hence, 95 by adjusting the bolts 19^b, 20^b, 19^d, 20^d, the beams 19 and 20 can be adjusted to any desired elevation with respect to the shafts 6, 7, and 8.

The inner ends of beams 19, 20, are provided intermediate the posts 1^a, 1^h, and 1^b, 1^j, with depending portions 19^e, 20^e provided with vertically disposed slots 20^f adapted to be engaged by bolts 21^a, 22^a, on horizontally disposed beams 21, 22, respectively disposed between the posts 1^a and the depending portion 19^e of beam 19, and between the post 1^b and the depending portion 20^e of beam 20 respectively, as shown in Figs. 1 and 3; said ends of beams 21, 22, adjacent depending portions 19^e, 20^e, being adjustably supported by bolts 21^b, 22^b, depending from brackets 19^g, 20^g on depending portions 19^e, 20^e. The ends of beams 21, 22 adjacent the uprights 1^a, 1^b, are supported by bolts 21^c, 22^c passing through end beam 1^k in a manner similar to bolts 19^b, 20^b, said ends of beams 21, 22 having bolts 21^d, 22^d on their sides engaging slots 1^t in the sides of posts 1^a, 1^b, for supporting the adjacent ends of beams 21 and 22 in proper adjusted position with respect to the shafts 2, 3, 4, and 5. Hence, by manipulating the bolts 21^b, 22^b and bolts 21^c, 22^c, the horizontal beams 21, 22 may be adjusted into and maintained in proper elevation to suit the thickness of the leather passing 110 through the machine.

Upon the beams 21, 22, are mounted parallel brush shafts 23, 24, 25, which are 130

preferably staggered, as shown in Fig. 3, with respect to carrier shafts 2, 3, 4, and 5; said shafts being mounted in vertically yieldable bearings as shown in Fig. 5, mounted on the tops of beams 21, 22. Each shaft 23, 24, 25 carries a brush 23^a, 24^a, 25^a, extending substantially the full length of the shaft between beams 21, 22, and by reason of their adjustable bearings, the brushes 10 may yield vertically in order to allow for different thicknesses of leather L inserted between the brushes, and the disks or wheels of the shafts 2, 3, 4, and 5. Mounted in bearings upon the sides of the depending 15 portions 19^e, 20^e, of the horizontal beams 19 and 20 is a brush shaft 26 parallel with shafts 23, 24, and 25 and carrying a brush 26^a, similar to brushes 23^a, 24^a, and 25^a. Mounted in bearings upon the beams 19 20 and 20 are three parallel brush shafts 27, 28, 29, said shafts carrying brushes 27^a, 28^a, 29^a respectively, similar to brushes 23^a, 24^a, 25^a and 26^a. Each of shafts 27, 28 and 29 25 is mounted similarly to shafts 23, 24, 25, in vertically yieldable bearings (Fig. 5) in order to permit the shafts to yield vertically, and thus allow for difference in the thickness of the leather L. In rear of shaft 29 is the power shaft 18 mounted in suitable 30 bearings upon beams 19 and 20, said shaft carrying a sprocket 18^b (Figs. 1 and 2) which is driven by a chain 18^c from a suitable prime mover shaft P, which may be the shaft of an electric motor or the like. 35 If desired, suitable reducing gearing (not shown) may be interposed between prime mover shaft P and the sprocket 18^b in order to reduce the speed of rotation of said shaft.

On the ends of shafts 23 and 24 are 40 sprockets 23^b and 24^b respectively, over which runs a chain 30, sprocket 24^b having one less tooth than the sprocket 23^b, whereby shaft 24 will rotate slightly faster than shaft 23. Similarly, a chain 31 runs over 45 sprockets 24^c and 25^b of shafts 24 and 25 respectively, sprocket 25^b having one less tooth than sprocket 24^c whereby shaft 25 will rotate slightly faster than shaft 24; also a chain 32 runs around sprockets 25^c 50 and 26^b on shafts 25 and 26 respectively, sprocket 26^b having one less tooth than sprocket 25^c; also a chain 33 runs around sprockets 27^b and 26^c on shafts 27 and 26 respectively, sprocket 27^b having one less 55 tooth than 26^c; also a chain 34 runs around sprockets 27^c and 28^b on shafts 27, 28, respectively, sprocket 28^b being smaller than 27^c; and a chain 35 runs around sprockets 28^c and 29^b on shafts 28, 29, sprocket 29^b 60 being smaller than 28^c whereby shaft 29 will rotate faster than shaft 28.

Shaft 29 is geared to drive shaft 18 by means of a gear 29^d meshing with a gear 18^d on drive shaft 18. Hence brush shafts 65 23, 24, 25, 26, 27, 28, and 29 each are driven

from drive shaft 18, each shaft commencing with shaft 23 being positively driven slightly faster than the preceding shaft.

Upon the horizontal beams 19 and 20 substantially directly over the uprights 1^h, 1^j, is a grooved oil roll 37^a mounted on a shaft 37, said roll 37^a contacting with brush 27^a. In the frame below 37^a is a pan 38 (Fig. 3) into which is fed the oiling compound, as hereinafter explained. The amount of oil 70 taken up from the pan 38 by roll 37^a is regulated by raising or lowering of roll 37^a so that the same will dip more or less into pan 38. Roll 37^a transfers the oiling compound 75 to brush 27^a, which spreads the compound upon the leather L passing thereunder and through the machine. Shaft 37 is provided on one end with a sprocket 37^b and a chain 39 passes over the sprocket 37^b and over a sprocket 18^e on the drive shaft 18, whereby 80 shaft 37 is rotated thereby.

Hot water is used in the scrubbing operation, the hot water being supplied through pipes 40 from a suitable source of supply, and discharged through spray pipes 41, disposed horizontally intermediate the brushes 23^a, 24^a, whereby the upper side of the leather L will be wetted as the leather passes through the machine as shown in Fig. 3, suitable valves (not shown) being interposed in pipes 40 for the purpose of regulating the amount of water discharged through spray pipes 41.

On the opposite side of the machine from the drive chains and sprockets are two oil containers C and C' (Fig. 2) which are connected at the lower ends through valved pipes 42, 43 with the inlet of an oil pump 44 rotated by a motor M, the pump outlet being connected with a pipe 45 which discharges into the oil pan 38 disposed beneath the oil roll 37^a. The oil compound may be pumped from either container C or C' and kept under constant flow through the pipe 45 into the pan 38. The oil compound is returned to the containers C or C' through an overflow or chain pipe 46 having valved branches 47 and 48. Only one barrel of compound is used at a time; this being regulated to opening or closing the valves in pipes 42, 43, 47, and 48. The oil compound is kept near the boiling point in the containers C and C' by means of steam coils 49 and 50 respectively which coils are supplied through valves 49^a and 50^a, with steam from a main 51. The use of the two containers C and C' renders available at all times one of the containers for use in mixing and preparing the compound, while the other container is being used to supply the pan 38 with the necessary compound to oil the leather.

In operation, the leather L is fed into the machine, lengthwise, between the carrier wheels 2^a and the brush 23^a, and the several

70

80

90

95

100

105

110

115

120

125

130

carrier shafts pull the leather L into the machine and move it on during the scrubbing and oiling operations. Brush rolls 23^a, 24^a, and 25^a, rotating at higher speeds than shafts 2, 3, 4, 5, scrub the leather for the purpose of cleaning it, while hot water introduced through pipes 40 from a hot water main is sprayed through the spray pipes 41 upon the top of the leather L. While the leather is wet with the hot water, the scrubbing brushes 23^a, 24^a, 25^a, clean it. These brushes also tend to smooth out any wrinkles in the leather, as do the carrier wheels 2^a, 3^a, 4^a, and 5^a, for the reason that every brush and every wheel moves at a slightly higher speed than the one preceding it, as above explained.

After the leather has been scrubbed, it then passes up the incline over wheels 9^a being guided by brush 26^a, and passes underneath pan 38, and then under brushes 27^a, 28^a, 29^a, the leather being moved by the underlying carrier wheels 6^a, 7^a and 8^a. Brush 26^a merely serves to guide the leather as it mounts the incline to pass underneath the pan 38.

The oiling compound is kept at a constant level in pan 38 by means of the overflow pipe 46, and the grooves in roll 37^a pick up the compound from the pan 38 and saturate the brush 27^a constantly therewith, the amount of compound to be placed on the leather being regulated by raising or lowering roll 37^a so that it will dip more or less deeply as desired into the pan 38. Roll 27^a brushes the compound on the leather, and rolls 28^a and 29^a brush the compound into the leather, so that when the leather finally emerges from the rear end of the machine it is thoroughly filled with the compound. It will be noted that all of the compound which is applied to the leather remains with it, and that none of it flows back into the pan 38, and hence no compound passes from the leather back into the containers C or C' and the compound is at all times clean and free from foreign matter.

Preferably one-third slippage is obtained between the brushes and carrier wheels to give the scrubbing effect and to rub the oil compound into the leather and also to smooth out any wrinkles which may exist in the leather. All of the brush shafts are mounted in bearings which are held down by coil springs and which may yield vertically to make wider openings between the rolls to accommodate leather of different thickness, or to make way for special wrinkles or "bunches" in the leather.

The machine is preferably geared down through several series of chains and sprockets so that the rolls rotate rather slow. This makes it unnecessary to use roller bearings in the machine. The bearings are oiled by any suitable means such as by tubes at one

end of the machine leading to the bearings and being provided with alemite valves or the like at their outer ends for greasing purposes.

The entire top portion of the frame of the machine, that is the portion which supports the upper layer or brush rolls, is made adjustable vertically for the purpose of taking up any wear on the brushes.

I do not limit my invention to the exact form shown in the drawings, for obviously changes may be made therein within the scope of the claims.

I claim:

1. In a leather scrubbing machine, a frame, a plurality of closely adjacent carrier wheels mounted in said frame for supporting the leather; a set of rotary brushes mounted in the frame above the carrier wheels, and adapted to contact with the leather; means for rotating the carrier wheels and brushes in the opposite directions to convey the leather through the machine; and means for wetting the leather passing through the machine.

2. In a machine as set forth in claim 1, frame members adjustably mounted above the carrier wheels; and said brush shafts being mounted on said members.

3. In combination with a machine as set forth in claim 1, means for oiling one of said brushes, comprising a cylinder rotatably mounted in the frame and adapted to contact with the said brush; and an oil pan cooperating with said cylinder.

4. In a leather scrubbing machine, a frame, a plurality of closely adjacent carrier shafts mounted in said frame carrying carrier wheels for supporting the leather; a set of rotary brushes mounted in the frame above said carrier wheels and adapted to contact with the leather; means for rotating the carrier and brush shafts in opposite directions to convey the leather through the machine; means for rotating each shaft of each set in the same direction and at a speed slightly greater than that of the shaft immediately preceding same; and means for wetting the leather passing through the machine.

5. In a machine as set forth in claim 4, said rotating means comprising sprockets mounted on the shafts of each set; chains running over the sprockets on the adjacent shafts in each set; the sprockets on each shaft in progression being smaller than the sprockets on the shaft immediately preceding same; a drive shaft mounted in the frame; and means for driving one shaft in each set from the drive shaft.

6. In a leather scrubbing machine, a frame, a set of shafts mounted in said frame; a plurality of carrier wheels mounted on said shafts, the wheels of each shaft overlapping the wheels of the adjacent

70

130

shafts; a set of rotary brushes mounted in the frame above said set of shafts; means for rotating the carrier and brush shafts in the opposite direction; and means for wetting the leather passing through the machine.

5 7. In a leather scrubbing machine, a frame, a set of parallel shafts mounted in said frame; a plurality of carrier wheels mounted on said shafts, the wheels of each shaft being staggered with respect to and overlapping the wheels of the adjacent shafts; a set of rotary brushes mounted in the frame above said carrier shafts; means for rotating the carrier and brush shafts in opposite directions; each shaft of each set being rotated in the same direction and at a speed slightly greater than that of the shaft immediately preceding same; and means for wetting the leather passing through the machine.

10 8. In a machine as set forth in claim 7 said rotating means comprising sprockets mounted on the shafts of each set; chains running over the sprockets on adjacent shafts in each set; the sprockets on each shaft in progression being smaller than the sprockets on the shaft immediately preceding same; a drive shaft mounted in the frame; and means for driving one shaft in 15 the two sets in opposite directions from the drive shaft.

15 9. In a leather scrubbing machine, a frame, a set of parallel shafts mounted in said frame; a plurality of carrier wheels of same diameter mounted on said shafts, the wheels of each shaft being staggered with respect to and overlapping the wheels of the adjacent shafts and adapted to convey the leather through the machine; a set of parallel rotary brushes mounted in the frame above said carrier shafts and adapted to contact with the leather; means for rotating the carrier and brush shafts in opposite directions; each shaft of each set being rotated in the same direction and at a speed slightly greater than that of the shaft immediately preceding same; the brush shafts being rotated at higher speeds than the carrier shafts; and means for wetting the leather passing through the machine.

20 10. In a machine of the character specified, a frame, a set of carrier wheels mounted in said frame for supporting a leather hide; a set of rotary brushes mounted in the frame above said carrier wheels and adapted to contact with the leather; means for rotating the carrier wheels and brushes in the opposite direction to convey the leather through the machine; and means for oiling the leather as it passes through the machine.

25 11. In a machine of the character specified, a frame, a set of carrier wheels mounted in said frame for supporting a leather

hide; a set of rotary brushes mounted in the frame above said carrier wheels and adapted to contact with the leather; means for rotating the carrier wheels and brush shafts in opposite direction to convey the leather through the machine; means for rotating the shafts of each set in the same direction and at a speed slightly greater than that of the shaft immediately preceding same; and means for oiling the leather as it passes through the machine.

30 12. In a machine of the character specified, a frame, a set of shafts mounted in said frame; a plurality of carrier wheels mounted on said shafts, the wheels of each shaft overlapping the wheels of the adjacent shafts; a set of rotary brushes mounted in the frame above said first set of shafts; means for rotating the carrier and brush shafts in the opposite direction; and means for oiling the leather passing through the machine.

35 13. In a machine of the character specified, a frame, a set of parallel shafts mounted in said frame; a plurality of carrier wheels mounted on said shafts, the wheels of each shafts being staggered with respect to and overlapping the wheels of the adjacent shafts; a set of rotary brushes mounted in the frame above said carrier shafts; means for rotating the carrier and brush shafts in opposite directions, each shaft of each set being rotated in the same direction and at a speed slightly greater than that of the shaft immediately preceding same; and means for oiling the leather passing through the machine.

40 14. In a machine as set forth in claim 13 said oiling means comprising a grooved cylinder rotatably and adjustably mounted in the frame and adapted to contact with one of said brushes; means for rotating said shaft; a pan mounted in the frame below the cylinder; a pair of oil reservoirs; overflow pipes connecting the pan and reservoirs; an oil pump; and pipe connections between the reservoirs, pan, and pump, whereby the pan may be supplied from either reservoir.

45 15. In a machine of the character specified, a frame, a set of parallel shafts mounted in said frame; a plurality of carrier wheels of same diameter mounted on said shafts, the wheels of each shaft being staggered with respect to and overlapping the wheels of the adjacent shafts and adapted to convey the leather through the machine; a set of parallel rotary brushes mounted in the frame above said carrier shafts and adapted to contact with the leather; means for rotating the carrier and brush shafts in the opposite directions; each shaft of each set being rotated in the same direction and at a speed slightly greater than that of the shaft immediately preceding same; the brush shafts being rotated at higher speeds than the car-

rier shafts; and means for supplying oil to one of the intermediate brushes to oil the leather passing through the machine.

16. In combination with a machine as set forth in claim 15, said oiling means comprising a grooved cylinder rotatably and adjustably mounted in the frame and adapted to contact with one of said brushes; means for rotating said cylinder; a pan mounted in the frame below the cylinder; a pair of oil reservoirs; steam coils in said reservoirs; a pump; a valved overflow pipe from the pan to the reservoirs; and valved pipe connections from the reservoirs to the 10 pan through the pump, whereby oil may be supplied to the pan from either reservoir.

In testimony that I claim the foregoing as my own, I affix my signature.

ELMER H. SMITH.
